WAYSIDE ACTUABLE SIGNAL SYSTEM

Chester W. Campbell, Anderson, Ind., and
Blanchard G. Chamberlain, Bellefontaine,
Ohio

Application April 16, 1945, Serial No. 588,464

11 Claims. (Cl. 246—174)

This invention relates to a system for railways and the like for the warning of the approach of a train to a highway crossing by whistle and/or bell.

The actuator for such an automatic system is a track side device for "picking-up" a signal indication. Herein such a device is positioned in advance of the crossing a sufficient distance to insure that the warning will be given prior to immediate crossing of the train at the crossing in question.

This system is arranged to fail on the side of safety, that is, failure of the intermediate device actuated by the pick-up signal will cause the bell and/or whistle to be actuated.

This system also is arranged to provide a permanent record of such warning signal and the exact signal given.

Since steam or air or electrically actuated bell ringing equipment and steam or air or electrically actuated whistling equipment are each old in the locomotive signalling art, no further mention herein is believed necessary, except to state that across the manually operable steam or air valve or switch for each, there is provided a by-pass including an electrically operable valve, such as a solenoid valve wherein, when the solenoid thereof is actuated, the valve actuated thereby is opened to supply steam or air to the warning device or there is provided a shunting switch in the circuit to warning device in question for operation thereof as long as such valve is held open by the solenoid or the switch is closed, respectively. Whenever the solenoid is not energized, the valve is closed. Thus, the automatic control does not and will not interfere with hand control as now employed. Since solenoid valves of this character are well known, no further reference will be had thereto, but merely the switch controlling the circuit including the solenoid will be described.

The chief object of this invention, accordingly, is to provide an automatic warning system for locomotives and the like.

The chief feature of this invention resides in the simplicity of construction of the unit and means incorporated therein for effecting said automatic operation.

Other objects and features of the invention will be set forth more fully hereinafter.

The full nature of the invention will be understood from the accompanying drawings and the following description and claims:

In the drawings, Fig. 1 is a wiring diagram of the control system circuits.

Fig. 2 is a side elevation of the relay and oppositely acting switch, the maintaining and resetting switches.

Fig. 3 is a rear elevation of the relay and oppositely acting switch.

Fig. 4 is a top plan view of the motor and motor operable portions of the control unit.

Fig. 5 is a side elevation of the coordinated recording and signal controls.

10 In Fig. 1, 10 indicates a track side inductor. The locomotive carries an inverted U-shaped receiver 12 comprising a magnet of laminated core type similar to inductor 10, each having pole faces 12a and 10a, respectively. About one leg of receiver 12 is a primary coil 13 and upon the other leg is a secondary coil 14.

A relay coil 15 has one terminal connected by line 16 to the source of potential 17 and branch 18 connects to one terminal of primary 13. The other terminal of primary 13 is connected by line 19 to source of potential 17. Branch 20 from line 19 connects to one terminal of secondary 14. The other terminal is connected by line 21 to one of two spaced contacts 22, the other being connected by line 23 to the other terminal of relay 15. Adjacent thereto is a pair of spaced contacts 24 and between both pairs is positioned bridging contact 25 carried by member 26 pivoted at 27 and constrained toward contacts 24 by spring 28. Member 26 mounts keeper 26a which, when relay 15 is energized, is attracted to the left and contact 25 now bridges contacts 22.

When so positioned, relay 15 is energized and this is the normal position of these parts unless 35 a failure occurs, or a wayside signal is received. As magnet 12 passes over inductor 10, the forces generated are such that relay 15 is deenergized so member 26 is released to spring 28, whereupon contact 25 bridges contacts 24. This opens the 40 circuit to the relay 15 so contact 25 can remain in bridging position across contacts 24.

Motor M has one terminal connected by line 29 to the source of potential 17. The other terminal is connected by line 30 to one contact 24, 45 the other being connected by line 31 to the source of potential 17. Therefore, when contact 25 bridges contacts 24, motor M is energized and the relay 15 circuit is open.

Upon motor energization, cam disk D rotates 50 so that notch D' moves from beneath switch Z, whereupon switch Z is closed by cam D. One terminal of the switch Z is connected to line 31. The other terminal is connected by line 32 to line 30. Switch Z, accordingly, is in parallel with contacts 24. Therefore, after the motor circuit is

initially closed across contacts 24, said circuit is maintained closed across switch Z until switch Z opens, which is when notch D' again registers with switch Z. This completes one revolution of cam D.

After the motor circuit is closed, rotation of cam D progresses until notch D' registers with member D² carried by one contact of switch Z'. Switch Z' is normally open as long as member D² rides the high portions of cam D. However, when member D² drops into notch D', switch Z' closes. Switch Z' is in parallel with contacts 22.

Accordingly, when switch Z' closes momentarily, the circuit to relay 15 is again closed. This opens the circuit across switch contacts 24, because member 25 now moves to the dotted position shown in Fig. 1. However, while the motor circuit is opened across contacts 24, it is still closed by switch Z and will remain closed until switch Z drops into notch D', whereupon the motor circuit 20 is opened and cam D rotation ceases.

Closing of the relay 15 circuit across contacts 22, because switch Z' has momentarily closed it, restores the relay circuit to normal condition, which is maintained until a failure occurs, or 25 another inductor 10 is traversed by receiver 12, whereupon the operation described is repeated.

Rotatable in timed relation with cam D, as hereinafter described are two cams A and B. Each cam has the desired contour, for example cam B has three long high portions and one short high portion, see Fig. 5. Adjacent each cam periphery is a pair of spring members 50-51 with contacts 50a and 51a adjacent each other. Finger 51 mounts follower 52. When same seats in a notch between high portions on the cam, the circuit across contacts 50a and 51a is opened. Leads 53 and 54 from the fingers 50 and 51 control 30 remotely, or are in series with a solenoid valve 35 hereinbefore mentioned.

In Fig. 1, leads 53a and 54a lead from one switch controlled by the cam A, and leads 53b and 54b lead from the switch controlled by cam B. The idle or stop position of cams A and B is such that followers 52 are seated in a cam low spot and the switch is open. When the motor is energized, the switch is closed and opened for one revolution of said cam A or B, as determined by the number and length of the high portions. Herein the arrangement is such that the whistle warning signal device is supplied with steam or air for two long periods, then a short period followed by a long period, the salient periods being of equal duration. The bell signal is continuous.

In Fig. 4 the motor M drives a worm 60 that rotates wheel 61, which is rigid with pinion 62 on shaft 63. Gear 64 on shaft 65 meshes with the pinion. Also, on shaft 65 are cams A, B and D aforesaid.

Also, on shaft 65 is secured gear 66 meshing with gear 67 rigid with shaft 68, which mounts spool 69, same being the rewind spool for tape 70 coming from supply spool or reel 71 carried by shaft 72. As shown, these spools are detachable or separable to remove printed tape and supply new rolls thereto when desired or required. Obviously, this tape is moved in timed relation with cam D and shaft 65.

Herein rigid with shaft 65 are a pair of printing rolls E and F. These have peripheries corresponding to those of cams A and B. A single transfer roll C below rolls E and F inks the high portions and the ink thereon is transferred to the tape 70 for record purposes. Roller C is associated with 75

ink well 80 directly as illustrated or indirectly through intermediate rolls as desired.

Obviously, the bell may not be rung continuously, in which event if cam A controls the bell 5 solenoid valve, there will be more than one low place in its periphery and also in the corresponding roll E periphery.

Obviously, whenever it is desired to operate the bell signal subsequent to the whistle signal, the bell circuit solenoid leads may energize, near the end of cam D rotation, a pick-up relay controlling a single cycle cam rotating motor, initial cam rotation thereby closing a motor maintaining circuit and also closing a bell control circuit. This 10 circuit also may be interposed in multiple with that specifically illustrated herein, so that bell ringing in this instance occurs with the whistling and continues after same ceases and for a predetermined period as determined by the second stage cam operation just described. In view of the previous description, neither additional description or illustration is believed necessary.

It will be clear that automatic signalling, as described, will not only warn all approaching the railway crossing of the approaching train, but such signalling will alert and warn the train crew of the highway crossing approach of the train. When the train is running too slow to give the legal signal aforesaid, two long, one short, one long in thirteen to fifteen seconds and within the required legal distance relative to the highway crossing, the engineer can press switch button 90, thus shorting out relay 15 and initiating the cycle whereupon operation follows as described previously.

For backing up, a second receiver on the opposite side of the locomotive may be employed. A cut over, or transfer switch, then would be mounted adjacent to and automatically operated 40 by the reversing gear to cut out the previous receiver and cut in the reverse receiver. Operation in that event will be as before described.

While the invention has been illustrated and 45 described in great detail in the drawings and foregoing description, the same is to be considered as illustrative and not restrictive in character.

The invention claimed is:

- 50 1. In an alarm system having alarm means, wayside signal means, and vehicle carried receiver means operatively associated with the signal means, the combination of an electric motor, cam means rotatable thereby, motor circuit maintaining normally open switch means cam operable to closed circuit position, motor circuit initiating normally open switch means, means for closing said last mentioned switch means upon operative association of the wayside signal means and receiver means, electrically operable means normally maintaining said closing means in motor circuit open circuit position, normally closed switch means in series with said electrically operable means and controlling same and conditioned for open circuit upon the aforesaid signal means and receiver means association, normally open, cam operable switch means in parallel with said series switch means for momentarily reenergizing the electrical operable means, cam operation thereof occurring subsequent to cam operation of the motor maintaining switch means, the closing means being common to the motor initiating switch means and the said series switch means and responsive to electrically operable means energization, means normally con-

- 60
- 65
- 70
- 75

straining the closing means to close the motor initiating switch means when the electrically operable means is effectively deenergized, and means operable in timed relation with said cam means and motor operable for controlling the alarm means.

2. A system as defined by claim 1 wherein a normally open manually operable switch is in multiple across the electrically operable means for manually short circuiting same to initiate motor operation when desired.

3. A system as defined by claim 1 wherein the electrically operable means is of relay type and the motor circuit initiating switch means and the series switch means each comprises a pair of spaced contacts and the closing means comprises a contact bridging member alternately bridging each pair of spaced contacts.

4. A system as defined by claim 1 wherein there is provided a plurality of independent alarm means, and a plurality of independent last mentioned means, one for each alarm means.

5. A system as defined by claim 1 wherein the last mentioned means comprises a rotatable cam and a normally open switch means controlling the alarm means, the cam having a plurality of switch closing portions, cam rotation repetitiously closing the last mentioned switch means.

6. A system as defined by claim 1 wherein the last mentioned means comprises a rotatable cam and a normally open switch means controlling the alarm means, the cam having a plurality of switch closing portions, cam rotation repetitiously closing the last mentioned switch means, the switch closing portions having the desired arcuate length whereby one revolution of the second mentioned cam produces the desired warning from the alarm means per first mentioned cam revolution.

7. A system as defined by claim 1 wherein there is provided a motor operable tape feeding device, an alarm indication printing means for tape printing and operable in timed relation with the alarm means.

8. A system as defined by claim 1 wherein there is provided a motor operable tape feeding device, an alarm indication printing means for tape printing and operable in timed relation with the alarm means, and comprising a printing wheel in tape contact and rotatable in timed relation with said cam.

9. A system as defined by claim 1 wherein there is provided a plurality of independent alarm means, a plurality of independent last mentioned means, one for each alarm means, a motor operable tape feeding device, a plurality of alarm indicating printing means for singular tape printing, one for each independent alarm means and corresponding to the independent means therefor, and operable in timed relation therewith.

10. A system as defined by claim 1 wherein the last mentioned means comprises a rotatable cam and a normally open switch means controlling the alarm means, the cam having a plurality of switch closing portions, cam rotation repetitiously closing the last mentioned switch means, a motor operable tape feeding device, and alarm indicating printing means for tape printing and operable in timed relation with the alarm means.

11. A system as defined by claim 1 wherein the last mentioned means comprises a rotatable cam and a normally open switch means controlling the alarm means, the cam having a plurality of switch closing portions, cam rotation repetitiously closing the last mentioned switch means, the cam switch closing portions having the desired arcuate length whereby one revolution of the second mentioned cam produces the desired warning from the alarm means per first mentioned cam revolution, a motor operable tape feeding device, and alarm indicating printing means for tape printing and operable in timed relation with the alarm means, and comprising a printing wheel in tape contact and rotatable in timed relation with said first mentioned cam.

CHESTER W. CAMPBELL.
BLANCHARD G. CHAMBERLAIN.
